(57) **CLAIM**

The ornamental design for a stylus pen case, as shown and described.

DESCRIPTION

FIG. 1 is a perspective view of a stylus pen case showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom perspective view thereof.

The unshaded inside surfaces of the stylus pen case, shown through the opening in FIGS. 1, 2, 6, and 8 and the broken line, form no part of the claimed design.

The dashed broken lines in the figures depict portions of the stylus pen case that form no part of the claimed design.

1 Claim, 8 Drawing Sheets
